UNITED STATES PATENT OFFICE

128,659

DESIGN FOR A WALL CABINET

Joseph H. Backert, Chicago, Ill.

Application July 15, 1940, Serial No. 93,657

Term of patent 7 years

To all whom it may concern:

Be it known that I, Joseph H. Backert, a citizen of the United States and a resident of Chicago, in the county of Cook and State of Illinois, have invented a new, original, and ornamental Design for a Wall Cabinet, of which the following is a specification, reference being had to the accompanying drawing, forming a part thereof, wherein:

Fig. 1 is a perspective view and Fig. 2 is a front elevational view of a wall cabinet embodying my new design.

I claim:

The ornamental design for a wall cabinet, as shown.

JOSEPH. H. BACKERT.
